F. A. HALLECK

FORGING MACHINE DEVICE

Filed May 9, 1917

Inventor:
Frank A. Halleck.
by Grace L. Halleck. Attest.

UNITED STATES PATENT OFFICE.

FRANK A. HALLECK, OF OAK PARK, ILLINOIS, ASSIGNOR TO SULLIVAN MACHINERY COMPANY, A CORPORATION OF MASSACHUSETTS.

FORGING-MACHINE DEVICE.

Application filed May 9, 1917. Serial No. 167,509.

To all whom it may concern:

Be it known that I, FRANK A. HALLECK, a citizen of the United States, residing at Oak Park, in the county of Cook and State of Illinois, have invented certain new and useful Improvements in Forging-Machine Devices, of which the following is a full, clear, and exact specification.

My invention relates to forging machines. 10 It has for its object to provide improved means whereby the axial opening in a hollow drill steel may be expanded, and more particularly whereby the same may be expanded during the manufacture or sharpening of such a steel. More specifically, my invention has for its object to provide improved and simplified means for expanding such an axial opening which is adapted conveniently to use in connection with the other 20 mechanism of a forging or sharpening machine and to application to such a machine at small expense and in such a manner that the power for operating the same is derived from that machine.

25 In the accompanying drawings, I have shown for purposes of illustration two embodiments which my invention may assume in practice.

In these drawings,—

30 Fig. 1 is a side elevation partially in section, of a portion of a drill sharpener equipped with my improvement.

Fig. 2 is an end elevation of a portion of the structure shown in Fig. 1, certain parts 35 being broken away to facilitate illustration.

Fig. 3 is a detail view partially in section, showing the hole opening mechanism expanding the hole in a drill steel.

Fig. 4 is a detail side elevation, partially 40 in section, showing a modified form of the construction shown in Fig. 3.

Fig. 5 is a plan view, partially in section, of this modified construction.

In this illustrative form of my invention, 45 I have shown the same applied to a drill sharpener of a well known type. As shown, this sharpener is mounted on a suitable frame or base 1, on which are carried swaging dies 2 and 3, of which the upper die 3 is 50 preferably adapted to be reciprocated relative to the lower die 2 in a well known manner, by means of a suitable motor, not shown, the reciprocation of the die 3 being controlled by suitable motor controlling mechanism of well known construction in-

cluding a link 4 and an operating foot lever 5. Cooperating with these swaging dies 2 and 3, and herein disposed in rear of the same, are clamping dies 6 and 7, of which the lower die 6 is stationary while the upper die 7 is carried on a vertically movable cross-head 8 connected by rods 8^a with a second crosshead 8', the latter being guided in suitable ways disposed in the bottom of the base or frame 1 and operated through a toggle connection 9 by a suitable horizontally disposed motor, not shown, connected to the toggle connection 9 through a sliding block 10 in such a manner as to cause the die 7 to be raised when the member 10 is pulled to the left, and to be lowered to clamping position, as indicated in dotted lines in Fig. 1, and as shown in full lines in Fig. 3 when that member is moved toward the right, this movement being controlled by a controlling lever 11 operatively connected to the toggle operating motor through its usual connections, not shown. As is usual in such a device, a dolly 12 operated by a striking pin 13 connected to a second horizontally acting motor, not shown, also controlled by the lever 11, is also so disposed adjacent the mouth of the die 6 that when the dies 6 and 7 are clamped together and the dolly is set in operation it may upset the end of a steel 75 80 85 90 95 100 105 110

In my improvement, I have provided means actuated by the movable crosshead 8 for expanding an axial perforation, as for instance that shown at 14 in Fig. 3, in the end of a drill steel at any time in the swaging or other forging operations. As shown, these means include a link 15 pivotally connected at 16 to a suitable forwardly extending bracket or extension 17 on the cross-head 8 and extending downward therefrom between the crosshead and the upper swaging die 3. Pivotally connected to the lower end of this link 15 is a pin 18, of any suitable cross section and preferably tapered as shown, which is reciprocable in a suitable passageway or recess in the lower swaging die block, herein shown in the form of an opening 19, and adapted to be projected through that opening out toward the front of the frame, as shown in Fig. 3, when the crosshead 8 is in its lowermost position shown in that figure, a portion 20 of the die 2 also preferably being cut away to permit the free movement of the link 15. By such

a construction, it will be noted that it is only necessary to operate the crosshead 8, as by means above referred to controlled by the operating lever 11, in order to cause the pin 18 to be projected out through the opening 19. Thus, by simply holding a drill steel against the face of the lower die 2 and opposite the opening 19 therein, the axial opening in the steel may be enlarged as and when desired, a very powerful action being obtained due to the toggle connection between the crosshead and the pin. It will also be noted that due to the location of this pin in the lower swaging die, it is not necessary for the operator to move the steel from its support or materially out of alignment with the other forging devices, the same being readily brought into alignment with the pin by simply depressing the forward end of the same. Attention is also directed to the fact that due to the toggle connection shown, the pin 18 is positively withdrawn from the steel, and that any difficulty with sticking of the pin within the steel is avoided as, when such sticking occurs, the withdrawing movement of the pin acts to draw the steel into engagement with the front face of the lower die block 2 and thus effectually separate the pin and steel without strain or other damage, or any effort on the part of the operator.

It will also be noted that in my improved construction I may provide, if desired, interlocking controlling mechanism between the controlling lever 11, which controls both the clamping die operating motor and the dolly operating motor, and the foot lever 5, which controls the motor for the swaging dies. As shown herein, this connection assumes the form of a link 27 pivoted at its upper end to the lever 11 and having its lower end movable in a guide 28 on the frame and adapted to cooperate with the foot lever 5 and prevent operation thereof in a predetermined position of the clamping dies. As shown, this lever 5 is pivoted at 29 and provided with an arm 30 thereon adapted to engage the lower end of the link 27 and thereby prevent the rotation of the pivot rod 29 and a crank 31 connected to the opposite end thereof and to the controlling mechanism for the swaging die motor. Thus, it will be noted that while the clamping dies are in clamping position and the operator is holding the steel against the front face of the lower swaging die to expand the hole in the steel, all danger or inconvenience arising from the operation of the swaging die motor is entirely overcome. Here, of course it will also be understood that, as in a well known construction, the downward movement of the lever 11 referred to above, while sufficient to operate the controlling mechanism for the clamping dies may not be sufficient to operate the controll-

ing mechanism for the dolly operating motor.

In Figs. 4 and 5, I have illustrated a modified form of the construction shown in Figs. 1, 2, and 3, wherein it will be noted that instead of utilizing a toggle I have provided a forwardly extending cam member 22 fixed to the crosshead 8 and movable therewith. This cam member I have shown as provided with an inclined surface 23 adapted to engage with the enlarged inner end 24 of a pin 25 freely reciprocable in a suitable recess in the lower die block 2 and normally held in retracted position and in the path of the surface 23 by a coiled spring 26. Obviously, in this construction when the crosshead 8 is lowered the action of the cam surface 23 will be such as to force the pin 25 forward against the tension of the spring 26 and project the pin through the block in such a manner as to enable it to open the hole in a steel held opposite the same. It will also be noted that, while in this construction the crosshead 8 will not positively pull the pin from the steel as the crosshead 8 moves upward carrying with it the cam surface 23, the operator will be able to free the steel from the pin by pulling on the same, and that as soon as the pin is released it will be returned to the position shown in Fig. 4, ready to be again engaged by the cam surface 23.

Due to my improved construction, it will be noted that the operator may very conveniently expand the hole in hollow drill steel at any time during the forging operation, the hole expanding or punching mechanism being located adjacent to and in substantial axial alignment with the other forging mechanism. It will also be evident that by simply manipulating the controlling lever 11 the punch may be operated at any time, and that through the provision of means connected to and moving with the powerful clamping dies, a very powerful punching action is obtainable. At the same time, attention is directed to the fact that the construction shown is exceedingly simple and of a type which can be manufactured and readily applied at small expense to a machine of standard construction. It will also be observed that by the provision of the clamping, upsetting, swaging and hole opening punch mechanisms in a vertically narrow horizontal zone, the various operations on a steel may be performed with much greater ease than would be the case were it requisite for a blacksmith to stoop over, or lift and lower bodily a steel during the process of sharpening, and that I have herein provided an arrangement, moreover, in which the steel being sharpened may be shifted from the position for one operation to that for another without substantial lowering of the whole steel. These and other advantages of

my improvement will, however, be clearly apparent to those skilled in the art.

While I have in this application specifically described two embodiments which my invention may assume in practice, it will be understood that the invention is not limited thereto and may be modified in such a manner as to assume various other forms without departing from its spirit, it being my intention to include all such modifications within the scope of the appended claims.

What I claim as new and desire to secure by Letters Patent is:

1. In a forging mechanism, a vertically movable clamping member, a horizontally reciprocable punch, and punch operating means carried by said clamping member.

2. In a drill sharpening mechanism, drill steel clamping mechanism including a stationary clamping member and a movable clamping member, a punch reciprocable in a direction parallel to that in which the axis of a steel would lie when clamped between said clamping members, and means actuated by said movable clamping member and constituting an operative connection between the same and said punch for actuating the latter.

3. In forging machine, a vertically movable clamping member, operating means therefor, an abutment having a horizontal recess therein, a punch reciprocable in said recess, and means carried by said clamping member for operating said punch.

4. In a forging mechanism, swaging mechanism including a swaging die having a recess therein, a punch reciprocable in said recess, and means for reciprocating said punch.

5. In a forging mechanism, swaging mechanism including a swaging die having a recess therein, a punch reciprocable in said recess, a vertically reciprocable crosshead, and means carried thereby for reciprocating said punch.

6. In a forging mechanism, swaging mechanism including a swaging die having a recess therein, a punch reciprocable in said recess, a vertically reciprocable crosshead, and means carried thereby for causing said punch to be projected from said recess.

7. In a forging machine, swaging mechanism including a swaging die, clamping mechanism including a reciprocable crosshead, a punch and punch operating mechanism operated by said crosshead and disposed between said mechanisms.

8. In a forging machine, swaging mechanism including a swaging die having a work engaging face, steel clamping mechanism including a reciprocable crosshead, and punching mechanism operated by said crosshead and disposed adjacent the work engaging face of said die in close propinquity thereto.

9. In a forging machine, swaging mecha-

nism including a recessed swaging die, steel clamping mechanism including a reciprocable crosshead, and punching mechanism operated by said crosshead reciprocable in the recess in said die.

10. In a forging mechanism, clamping mechanism including a reciprocable member, swaging mechanism including a swaging die arranged adjacent said clamping mechanism, a punch disposed adjacent the work engaging portion of said die, and means carried by the movable member of said clamping mechanism for operating said punch.

11. In a forging mechanism, clamping mechanism including a reciprocable member, swaging mechanism including a swaging die arranged adjacent said clamping mechanism, a punch disposed adjacent the work engaging portion of said die, and means forming a toggle connection connected to said punch and carried by the movable member of said clamping mechanism.

12. In a forging mechanism, clamping, upsetting, and swaging mechanisms disposed in substantial axial alignment, a punch disposed in substantial axial alignment with said mechanisms, and means connected to one of said mechanisms for operating said punch.

13. In a forging mechanism, clamping, upsetting, and swaging mechanisms disposed in substantial axial alignment, a punch disposed in substantial axial alignment with said mechanisms, and means connected to said clamping mechanism for operating said punch.

14. In a forging mechanism, clamping mechanism, upsetting mechanism, swaging mechanism including a swaging die having a recess therein, said mechanisms being disposed in substantial axial alignment, a punch movable in said recess, and means connected to one of said mechanisms for reciprocating said punch.

15. In a forging mechanism, a clamping mechanism, upsetting mechanism, swaging mechanism including a swaging die having a recess therein, said mechanisms being disposed in substantial axial alignment, a punch movable in said recess, and means connected to said clamping mechanism for reciprocating said punch.

16. In a forging mechanism, clamping mechanism, upsetting mechanism, swaging mechanism including a swaging die having a recess therein, said mechanisms and recess being disposed in substantial axial alignment, a punch movable in said recess, and means connected to said clamping mechanism for reciprocating said punch in opposite directions.

17. A machine of the character described comprising upsetting mechanism including

a movable clamping member, swaging mechanism arranged adjacent said upsetting mechanism and including fixed and movable members, and opening expanding mechanism including a reciprocating punch moving in the fixed member of said swaging mechanism.

18. A machine of the character described comprising upsetting mechanism including 10 a movable clamping member, swaging mechanism arranged adjacent said upsetting mechanism and including fixed and movable members, and opening expanding mechanism arranged immediately adjacent said upsetting and swaging mechanisms and including a reciprocating punch operated by said movable clamping member.

19. A machine of the character described comprising upsetting mechanism including 20 a movable clamping member, swaging mechanism arranged adjacent said upsetting mechanism and including fixed and movable members, and opening expanding mechanism arranged immediately adjacent said upsetting and swaging mechanisms and including a reciprocating punch guided for movement in the fixed member of said swaging mechanism.

20. A machine of the character described comprising upsetting mechanism including 30 a movable clamping member, swaging mechanism arranged adjacent said upsetting mechanism and including fixed and movable members, and opening expanding mechanism arranged immediately adjacent said upsetting and swaging mechanisms and including a reciprocating punch guided for movement in the fixed member of said swaging mechanism and operated by said movable clamping member.

21. In a machine of the character described, swinging mechanism including a swaging die, opening expanding mechanism including a punch carried by said swaging die, and means for preventing operation of said swaging mechanism when said expanding mechanism is operated.

22. In a forging machine, a motor actuated swaging mechanism including a stationary die, motor actuated opening expanding mechanism including a punch carried by said stationary die, control means for said mechanisms, and locking mechanism for the control means of said swaging mechanism operated by movement of the control means for said opening expanding mechanism.

23. In a forging machine adapted for the

sharpening of drill steels, swaging mechanism including a swaging die, opening expanding mechanism including a punch disposed in close juxtaposition to the working face of said die, and means for preventing operation of said swaging mechanism when said opening expanding mechanism is operated.

24. In a forging machine adapted for the sharpening of drill steels, swaging mechanism including a swaging die, opening expanding mechanism including a punch disposed in close juxtaposition to the working face of said die, control means for said swaging and opening expanding mechanisms, and an interlock between said control means to prevent simultaneous operation thereof.

25. In a drill sharpening mechanism, drill steel clamping mechanism including a stationary clamping member and a movable clamping member, a punch reciprocable in a direction at an angle to the direction of movement of the movable clamping member, and means actuated by said movable clamping member and constituting an operative connection between the same and said punch for actuating the latter.

26. In a drill sharpening machine, swaging mechanism including stationary and movable swaging dies providing cooperating bit forming recesses, clamping means including relatively movable members cooperating to form a steel holding recess, upsetting mechanism including a work engaging member, and a hole opening punch, said parts being constructed and arranged so that said recesses, said work engaging member, and said punch lie in a vertically narrow horizontal zone.

27. In a drill sharpening machine, swaging mechanism including stationary and movable swaging dies providing cooperating bit forming recesses, clamping means including relatively movable members cooperating to form a steel holding recess, upsetting mechanism including a work engaging member, and a hole opening punch, said parts being constructed and arranged so that said recesses, said work engaging member, and said punch are so disposed that an operator standing in front of the drill sharpening machine may shift a steel being sharpened from one to another thereof without substantial lowering of the whole steel.

In testimony whereof I affix my signature.
FRANK A. HALLECK.
